UNITED STATES PATENT OFFICE.

HENRY C. HINCHCLIFF, OF BROOKLYN, NEW YORK.

RIVET MANUFACTURE.

1,388,566.

Specification of Letters Patent. Patented Aug. 23, 1921.

Application filed May 3, 1920. Serial No. 378,464.

To all whom it may concern:

Be it known that I, HENRY C. HINCHCLIFF, a citizen of the United States, and a resident of the borough of Brooklyn, county of 5 Kings, and State of New York, have invented new and useful Improvements in Rivet-Manufacture, of which the following is a specification.

The object of this invention is to provide 10 means in a rivet heading machine for making tubular and pronged rivets which have heretofore been respectively drilled and sawed after leaving the heading machine.

This invention relates to that class of machines in which a reciprocating hammer or press is employed to head rivets and in which one or more dies are carried by the hammer to form the head of the rivet by giving one or more blows with each die 20 and particularly to that class of machines in which an ejector is employed to remove the rivet from the dies after it is finished and will be shown and described herein as adapted to a machine having two dies carried by the hammer, such being generally used for making this class of rivets.

My present invention relates to the manufacture of rivets and consists of an improved method of manufacture which comprehends 30 an improved initial distribution or disposition of metal whereby the final steps or operations to complete the rivets may be performed more successfully and with greater facility and uniformity as a result thereof. 35 My invention further consists of improved means adapted to form the rivets in accordance with my improved method and to secure the advantages thereof.

In accordance with my improved method 40 of manufacture, the rivet blank is formed in the initial operation of heading to produce a body wherein the metal is distributed in proportion to the final disposition, whereby the extrusion of the metal may be effected without excessive or undue distortion and movement of the metal thereof.

Furthermore in accordance with my invention the metal to be extruded is reduced in cross sectional area with relation to the 50 body of the rivet whereby the latter offers greater resistance to distortion or displacement and in consequence will properly sup-

port or back up the portion to be extruded without effect thereon, and in my improved means and arrangement the solid portion of 55 the rivet body will moreover be supported within the die during the extrusion operation thus further insuring against its distortion.

Important features of my improvements 60 consist in forming the blank receiving die with a portion of a cross area adapted to hold enough metal only to form the tube or prongs of a rivet and which may later be extruded to the size of the rivet body by 65 a punch or ejector being forced thereinto.

Other improvements consist in an ejector adapted to pierce the rivet body longitudinally. In means for adjusting the lateral position of an ejector located within the 70 blank receiving die thereby regulating the length of the portion adapted to receive metal for the tube or prongs of a rivet.

Means for compressing a rivet body longitudinally between an ejector and a heading die after the head is formed and means 75 for regulating the said compression.

It being understood that the said adjusting and regulating means are arranged to act while the machine is in operation. 80

A peculiar advantage of these improvements resides in indenting the end of a relatively reduced portion of a rivet body when formed in the initial operation of heading, so that later a punch is thereby 85 centrally piloted to pierce and extrude the reduced portion and to thus form a tube concentric with the body.

The described and other features of my invention are illustrated in the accompanying drawings wherein like reference characters are applied to the corresponding parts in the several views—

Figure 1 is a sectional view of an anvil 1, a holding or blank receiving and body forming die 2, an ejector 3, and showing a rivet 4, after the end has been reduced at 2^A, and a head formed by a blow of a heading die. 95

Fig. 2 is a sectional view of a reciprocating hammer 5, a die carrier 6, a centering 100 die 7, and a finishing die 8.

Fig. 3 is a sectional view of the anvil, the holding die, the ejector, the hammer and die carrier and the centering and finishing

dies, the rivet is here shown after the head has been formed by the finishing die and compressed longitudinally between the ejector and the finishing die.

5 Fig. 4 is a sectional view of the anvil, the holding die, the ejector, with a finished rivet pushed from the holding die and a stripper 9, moved under the head of the rivet.

Fig. 5 is a plan view of the same.

10 Fig. 6 is a plan and side view partly in section of a four prong rivet.

Fig. 7 is a view in perspective of an ejector adapted to form a four prong rivet.

15 Figs. 8 and 9 are plan and side views partly in section of tubular rivets.

In this process of rivet making a rod of metal of the size of the rivet body is fed into the machine and a piece long enough to form a rivet is sheared therefrom—then 20 fed to and formed into shape by the dies and then ejected therefrom which completes the process.

To insure the forming of true heads, one 25 of the hammer dies is socket shaped—This precedes the finishing die and holds the body of the rivet in line while being shouldered and a head formed against the holding die, then this centering die is slid out of line of the work as the finishing die 30 is moved into line, and the next blow of the hammer upsets therewith the rivet head in proper shape and the rivet is thereafter ejected.

In my improved machine, the holding die 35 2, is adapted as shown at 2^A, Fig. 1, to form the body of the rivet as it is forced therein when a head is formed by the centering die 7, and the body of the rivet may be lengthened more or less by adjusting the position 40 of the ejector 3, at this point.

The point of the ejector is adapted as shown at 3^A, Fig. 1 to pierce and extrude the body of the rivet when pressed thereinto while it is in an enlarged section of the die 45 2 as shown at 2^B, Fig. 3.

The operation of the machine is as follows, after a rivet-blank is cut and fed to the holding die 2, it is struck by the heading dies thus forcing rivet-blank thereinto and 50 reducing the body of the rivet as shown at 2^A, Fig. 1, after the head of the rivet is finished and while the heading die 8 with the carrier 6, and hammer 5 are receding, and while the reduced portion of the rivet 55 body is located within the holding die, the ejector 3, with the rivet is advanced enough more than the heading die 8 recedes to force the ejector 3, into the reduced end of the rivet body thus piercing it and extruding 60 the metal to fill the holding die 2, as shown at 2^B, Fig. 3. Thereafter, the heading die 8 continues to recede and the ejector 3, pushes the finished rivet from the holding die 2, as shown in Fig. 4 the stripper 9 is 65 then moved under the rivet head as shown,

and the ejector 3 is then withdrawn thus completing the cycle of operations.

I have described these embodiments of my invention as applied to solid and non-separable dies but split or separable dies 70 may be used where it is desirable, as for instance in the making of long rivets, without departing from the spirit of the invention, and I do not limit myself solely to such applications as are herein shown for it is 75 intended that all matter herein contained shall be interpreted as illustrative and not in a limiting sense.

Having thus described my invention what I claim is:

1. The herein described method of manufacturing rivets which consists in initially forming the portion thereof to be extruded of reduced cross sectional area with relation to the body of the rivet and subsequently extruding said portion substantially as described.

2. The herein described method of manufacturing rivets which consists in initially forming the portion thereof to be extruded 90 of reduced cross sectional area with relation to the body of the rivet and subsequently extruding said portion substantially as described while supporting the body of the rivet in alignment with extruding means.

3. In a rivet making machine, dies adapted to head a rivet-blank and to form a body provided with a portion of relatively reduced cross sectional area and means for piercing after the head and body are formed 100 the said reduced cross sectional area longitudinally with the body of the rivet and therewith extruding radially metal from the center of the rivet body.

4. In a rivet making machine, dies adapted 105 to receive and head a rivet blank, and to form a body having a portion of a relatively reduced cross sectional area, means for piercing longitudinally the reduced portion of the rivet body after it is headed and means 110 for stripping the rivet from the piercing means substantially as described.

5. In a machine of the character described, heading dies, a rivet blank receiving die adapted to form a rivet body having a portion of a relatively reduced cross sectional area, and an ejector arranged in concentric alignment with the blank receiving die adapted and arranged to pierce a rivet body 115 after it is headed, and adapted for adjustment for the purpose of regulating the length of the reduced portion of the rivet body substantially as described.

6. In a machine of the character described, a rivet blank receiving die adapted to form 125 a rivet body having a portion of a relatively reduced cross sectional area, and means adapted for positioning, dividing, and extruding the reduced portion of the rivet body.

7. In a rivet making machine, dies adapted to form a rivet having a body provided with a portion of a relatively reduced cross sectional area, and a punch arranged and adapted initially, to indent centrally the said reduced portion of the rivet body when it is formed, and operable to pierce and extrude the said reduced portion of the rivet body

while it is positioned free of its forming walls.

In witness whereof, I have signed my name to the foregoing.

Dated April 29th, 1920.

HENRY C. HINCHCLIFF.

Witness:

C. L. BACKER.
